REFRIGERATED ENCLOSURE FOR MAKING AND STORING ICE PRODUCTS

Martin Kenney, Donald S. Scott, and Lewis A. Weed,
Sau Jose, Calif., assignors to S & S Vending Machine
Co., San Jose, Calif., a corporation of California

Filed Oct. 11, 1963, Ser. No. 315,439

2 Claims. (Cl. 62—341)

The present invention relates in general to ice vending stations, and more particularly to a method of and apparatus for producing ice, such as block ice and crushed ice.

Ice vending stations are very frequently located in the parking areas of supermarkets and service stations. Basically, an ice vending station is an enclosure for storing and vending ice products. A customer deposits a coin in the meter provided and an ice product is automatically discharged through a chute.

Heretofore, such ice vending stations failed to provide block ice for the customers. The reason is two-fold. Firstly, block ice supply companies are substantially reduced in number so that few communities still have a source for supplying block ice. Secondly, such ice vending stations were incapable of producing block ice. It follows, also, that such ice vending stations did not produce the block ice for converting the same into crushed ice.

Accordingly, an object of the present invention is to provide an ice vending station that produces block ice for the self-service, automatic vending thereof.

Another object of the present invention is to provide an improved method for producing block or solid ice.

Another object of the present invention is to provide a method for producing block or solid ice wherein the block or solid ice, when formed, is packed within a container for vending.

Another object of the present invention is to provide improved apparatus for the producing of block ice within an ice vending station.

Another object of the present invention is to provide an improved ice vending station.

Other and further objects and advantages of the present invention will be apparent to one skilled in the art from the following description taken in conjunction with the accompanying drawings, in which:

FIG. 1 is a perspective view of the ice selling station of the present invention.

FIG. 2 is an enlarged horizontal sectional view taken along lines 2—2 of FIG. 1 to illustrate the ice producing portion of the ice vending station and the ice vending and crushing portion of the ice vending station.

FIG. 3 is a vertical sectional view taken along line 3—3 of FIG. 2 to further illustrate the ice producing portion of the ice vending station.

FIG. 4 is a vertical sectional view taken along line 4—4 of FIG. 2 to further illustrate the ice vending and crushing portion of the ice vending station.

FIG. 5 is an enlarged view taken along line 5—5 of FIG. 3 to illustrate the forming of block ice in buckets for crushing and the forming of block ice in bags.

FIG. 6 is a fragmentary view taken along line 6—6 of FIG. 5 to further illustrate the forming of block ice in buckets and the forming of block ice in bags.

FIG. 7 is a perspective view of block ice formed in a bucket.

FIG. 8 is a perspective view of block ice formed in a bag.

Illustrated in FIGS. 1—4 is the ice vending station 10 of the present invention which comprises a transportable insulated structure 11. The insulated structure 11 in-

2

cludes side walls 14 and 15, end walls 16 and 17, a floor 18, and a ceiling 19. Formed in the end wall 17 is a suitable door 20 to permit ingress into the vending station 10 and egress from the vending station 10. The entire structure is suitably insulated to retain the area within the ice vending station 10 at temperatures suitable for storing ice.

As shown in FIG. 4, a conventional and well-known conveyor system 30 for ice vending stations is mounted within the ice vending station 10. The conveyor system 30 is divided into two sections, each section operating independently. On the upper runs of one conveyor section are disposed bags of block or solid ice 31 and on the upper runs of the other conveyor section are disposed bags of crushed ice 32. A purchaser inserts designated coin or coins into a suitable and conventional meter located at selector area 40 (FIG. 1) in the end wall 16 and selects either crushed ice or block ice. Thereupon, the conveyor system 30 (FIG. 4) is operated through a suitable motor, not shown, and control circuit, not shown, to advance the selected ice product for discharge through a chute 41 (FIG. 1) associated with the end wall 16. The foregoing is well-known and conventional for ice vending stations.

For maintaining the atmosphere within the ice vending station 10 at temperatures suitable for storing ice, such as between 24—28 degrees Fahrenheit, a conventional blower 45 (FIGS. 2 and 3) and a suitable compressor 46 are provided. Conventionally, ice selling stations include such a compressor and blower for maintaining the temperature therein suitable for storing ice.

According to the present invention, block or solid ice is formed and produced within the ice vending station 10. Toward this end, a freezing compartment 50 (FIGS. 2, 3 and 5) is disposed within the ice vending station 10, which compartment comprises side walls 51 and 52. At one end of the freezing compartment 50 is located an end wall 53. At the opposite end of the freezing compartment 50 is positioned a tunnel 55 (FIG. 3). The compartment 50 includes a bottom wall 50'. Suitable sliding and removable top panels, not shown, are resting on the side walls 51 and 52 to enclose the compartment 50. All the walls and panels of the compartment 50 are suitably insulated to maintain the temperature within the compartment 50 between zero and eight degrees Fahrenheit, which in the preferred embodiment is the temperature for converting water into block ice.

As shown in FIGS. 2, 3, 5 and 6, longitudinally extending, channel-shaped shelves 61—63 are disposed in juxtaposition within the compartment 50. The shelves 61—63, which are made of suitable metallic material, are supported by and rest upon a horizontal plate 64 (FIGS. 3 and 6) that is fixed to the interior surfaces of the side walls 51 and 52 of the compartment 50. It is to be observed that the horizontal plate 64 is spaced above the bottom wall 50' and does not extend as far as the end wall 53, thus leaving a space therebetween.

The compartment shelves 61—63 comprise respectively bases 61a—63a. Integrally formed with the base 61a are upright, yieldable partitions 61b and 61c. Horizontally disposed flanges 61d and 61e project from the partitions 61b and 61c, respectively. Similarly, integrally formed with the base 62a are upright, yieldable partitions 62b and 62c. Horizontally disposed flanges 62d and 62e project from the partitions 62b and 62c, respectively. The flange 61e is superposed over the flange 62d. Likewise, integrally formed with the base 63a are upright, yieldable partitions 63b and 63c. Horizontally disposed flanges 63d and 63e project from the partitions 63b and 63c, respectively. The flange 62e is superposed over the flange 63d.

Disposed within the tunnel 55 (FIG. 3) is a conventional blower 70 and adjacent thereto is a conventional compressor 70'. In this manner, cold air from zero to eight degrees Fahrenheit is circulated through the compartment 50 above the horizontal plate 64 in a path shown by the direction of arrows 71 (FIG. 3) and the air so circulated has a return path to the tunnel 55 between the lower surface of the horizontal plate 64 and the bottom wall 50'.

Adjacent the wall 17 is a water tap 72 (FIGS. 2 and 3) that is connected to a suitable supply of water by way of a fitting 73. When desired a convenient hose may be connected to the tap 72. Located adjacent the wall 14 and in the vicinity of the conveyor system 30 is a conventional and well-known ice crusher machine 75 (FIGS. 2 and 4) that converts block ice into crushed ice.

Shown in FIGS. 5-7 are buckets or pails 80, which are suitable for containing water to be frozen into block or solid ice. Also included in the ice vending station 10 is a supply of bags such as bags 82 suitable for containing water to be frozen into block or solid ice. In addition, the bags 82 are suitable for holding crushed ice. The bags 82 may be made from plastic, polyethylene or impervious material suitable to contain water and ice.

In the method of the present invention, an operator fills a number of bags 82 with water from the tap 72. Thereupon, the operator places the water-filled bags in the freezing compartment 50 on the shelves 61, 62, 63 in an upright position. During this time, the compressor 70' and the blower 70 are operating so that the air circulated through the compartment 50 above the plate 64 is between zero and eight degrees Fahrenheit. The water-filled bags remain within the freezing compartment 50 a sufficient period of time to permit the water in the bags 82 to be converted into block or solid ice.

Also, an operator may fill the buckets 80 from the tap 72 and place the water-filled buckets on the plate 64 within the compartment 50. The water-filled buckets remain within the freezing compartment 50 a sufficient period of time to permit the water in the buckets 80 to be converted into block or solid ice.

When the bags filled with block or solid ice are ready to be removed from the compartment 50, the operator urges the yieldable partitions of each respective shelf in a direction to increase the distance between associated partitions for facilitating and rendering easy the removal of the bags containing block or solid ice from the compartment 50. Upon release, the partitions for the shelves 61-63 return to their initial positions.

The block ice 31 contained by the bags 82 is removed by an operator from the compartment 50. Thereupon, the operator carries the bags with block ice and places the same on designated upper runs of the conveyor system 30. The block ice 31 has flat upper and lower surfaces with substantially oval horizontal cross-sectional areas.

In addition, the buckets 80 containing block ice are removed by an operator from the compartment 50. Such block ice is removed from the buckets and put into the machine 75, whereupon such block ice is crushed into

crushed ice. The crushed ice 32 is packed into the bags 82 and the operator closes the mouth of the bags. The mouths of the bags are secured by tape or string and an operator then places the same on designated upper runs of the conveyor system 30. The compressor 46 and blower 45 are continuously operating to maintain the ice vending station 10 between 24-28 degrees Fahrenheit.

A purchaser inserts a predetermined coin or coins in a meter located at the selector area 40 and selects either crushed ice or block ice. Thereupon, the conveyor system 30 is operated to advance the selected ice product for discharge through the chute 41.

It is to be understood that modifications and variations of the embodiment of the invention disclosed herein may be resorted to without departing from the spirit of the invention and the scope of the appended claims.

Having thus described our invention, what we claim as new and desire to protect by Letters Patent is:

1. An ice vending station comprising a freezing compartment, a horizontal plate mounted in said compartment intermediate the upper and lower extremities thereof, a plurality of removable shelves disposed within said compartment and seated on said plate, said shelves being formed with yieldable upstanding partitions, a plurality of bags filled with water disposed on said shelves within said compartment, and cooling means for circulating cold air through said compartment over a path located above said plate and returning said circulated air over a path below said plate for converting the water in said bags into block ice, said yieldable partitions being adapted to be urged away from one another to facilitate the removal of a bag containing block ice from the shelf supporting it.

2. A freezing compartment comprising a horizontal plate mounted in said compartment intermediate the upper and lower extremities thereof, a plurality of removable shelves seated on said plate, said shelves being formed with yieldable upstanding partitions, a plurality of bags filled with water disposed on said shelves, and cooling means for circulating cold air through said compartment over a path located above and below said plate for converting the water in said bags into block ice, said yieldable partitions being adapted to be urged away from one another to facilitate the removal of a bag containing block ice from the shelf supporting it.
